UNITED STATES PATENT OFFICE

2,589,036

TIE HOLDER

Frank M. Bender, Evanston, Ill.

Application July 19, 1950, Serial No. 174,639

9 Claims. (Cl. 24—49)

1

The present invention relates to neck-tie holders.

One object of the invention is to provide a holder which is applicable to the ends of a four-in-hand tie and is adapted to hold the wide front end of the tie in symmetrical shape and secure it against displacement relatively to the wearer's shirt.

Another object of the invention is to provide a tie holder which is completely concealed when in use.

Another object of the invention is to provide an improved tie holder whereby the wide front end and the narrow back end of the tie will be individually secured against displacement relatively to each other and to the shirt.

Another object of the invention is to provide a neck-tie holder whereby the wide and narrow ends of the tie will be firmly secured in desired position on the wearer's shirt.

A further object of the invention is to provide a neck-tie holder which includes a two-way bow-spring for alternately securing and releasing the gripping members in their open and closed positions.

A still further object of the invention is to provide a neck-tie holder which is generally of new and improved construction and is characterized by high efficiency, ease of application and removal and cheapness of manufacture.

Other objects of the invention and the various advantages and characteristics of the present tie holder will appear from the following detailed description.

The invention consists in the several novel features which are hereinafter set forth and are more particularly defined by claims at the conclusion hereof.

In the drawing which accompanies and forms a part of the present specification and in which like numerals of reference denote corresponding parts throughout the several views:

Fig. 1 is a plan view of a tie holder embodying the invention in its tie-releasing or tie-inserting position, the tie and shirt being indicated by dotted lines in position to be gripped when the holder is closed;

Fig. 2 is a plan view showing the holder in tie-gripping or closed position;

Fig. 3 is a perspective view of the back member of the holder;

Fig. 4 is a detail perspective view of the bow-spring;

Fig. 5 is a perspective view of the front member of the holder;

2

Fig. 6 is a perspective view of the clip for connecting the back member and the bow-spring;

Fig. 7 is a front view of a tie, illustrating by dotted lines the position of the concealed holder; and

Fig. 8 is a transverse section of the holder taken on the line 8—8 of Fig. 2.

The invention is exemplified in a tie-holder which comprises generally a back gripping member generally designated 15, for the small end of a four-in-hand tie and a portion of the front of the wearer's shirt, a front gripping member generally designated 17, for holding the large end of the tie in symmetrical shape and for holding said end against the back member, and a two-way bow-spring 19, for alternately holding the front and back members in their open position for receiving the tie ends and in their closed position wherein they hold the tie ends in place.

20 The back member 15 is formed of a flat strip of suitable resilient metal and includes a forwardly bowed back section 21 with a rearwardly and inturned loop 22 which is adapted to be inserted between lapped panels 10 and 11 of the shirt front, and a forwardly bowed front section 23 which is joined to the section 21 by an integral U-shaped bend 24 and is adapted to clamp the small end 12 of the tie and the panel 10 of the shirt against the front face of back section 21.

25 The bow-spring 19 is formed of a flat strip of spring metal, such as steel, is normally straight, and is adapted while its ends are restricted against relative outward movement to exert spring pressure for either urging the front member 17 against the front face of the front section 23 while the bow spring 19 is bowed forwardly for holding the front member 17 away from the front section 23 when the spring is bowed rearwardly. In this manner the bow-spring is adapted for

30 alternately applying forward and rearward pressure to the front member 17. The front member 17 fits between the front 13 and inturned folds 14 of the wide end of the tie, is formed of a flat strip of suitable metal, is forwardly bowed, and 35 is provided with rearwardly and inwardly extending hooks 28 in which the ends of the bow-spring 19 are seated. The hooks 28 are centrally provided with notches 29 into which small tongues 30 on the ends of bow-spring 19 extend, for transversely interlocking the spring and member 17. This arrangement for interlocking the parts serves as securing means for retaining bow-spring 19 in either a forwardly flexed position or a rearwardly flexed position. The front section 23 of 40 the back member 15 is provided with a forwardly

extending offset 31. A C-shaped clip 32 formed of a strip of flat metal, extends across the front face of the bow-spring 19, around the upper and the front lower edges of said spring and section 23 is confined in the back of the offset 31 and serves to lock or secure together the central portions of the front section 23 and the bow spring 19, while leaving the outer portions of said spring free to be flexed in opposite directions.

In some instances it may be desirable more positively to secure the tie and shirt in the holder than by clamping pressure alone, and for this purpose a pair of laterally spaced pins 40 and 41 are fixedly secured to the front member 17 so that they project rearwardly therefrom. These pins, when the holder is in its closed position as shown in Fig. 2, extend through holes 33 in the bow spring 19, the infolds 14 of the wide end of the tie, holes 34 in section 23, and into the narrow end 12 of the tie and the panel 10 of the shirt panel that is between the back and front sections 21 and 23. The pin 40 is adapted to extend through the shirt panel and the narrow end of the tie and also through a hole 45 in the end portion of the back section 21 that has the loop 22. The loop 22 serves as a guard for the inner end of pin 40. The pin 41 terminates forwardly of the back section 21 so it will be guarded thereby.

While the bow spring 19 is forwardly bowed, the hook 28 of the front member 17 will restrict outward movement of the ends of the spring so that it will be held bowed forwardly and will yieldingly urge and hold the member 17 in its open position (see Fig. 1). While the spring 19 is rearwardly bowed, the hook ends 28 will restrict the ends of the spring 19 so that the spring will be urged to increase its bow and to press the member 17 backwardly toward the front section 23 of the back member 15, and hold the member 17 in its closed position (see Fig. 2).

To facilitate the spreading of the members 15 and 17 to release the tie, a device is provided for prying the front member 17 away from the back member 15 a sufficient distance to snap the bow spring 19 across its dead center so its direction of pressure will be so reversed as to shift the member 17 away from the member 15 and yieldingly hold said members spaced apart sufficiently for the easy insertion of the member 15 and the spring 19 between the front 13 and the folds 14 of the wide end of the tie, as shown in Fig. 1. This spreader device comprises a pair of fingers 36 which have back turned right angle ends 37 and are welded to the inner ends of a pair of resilient strips 38. The latter have their outer ends welded to the front face of the bow-spring 19. When the holder is in its closed position as shown in Fig. 2, the ends of the fingers 36 can be pressed backwardly to cause the fingers to fulcrum on the upper and lower ends of the clip 32, twist the strips 38 and pry the central portion of the front member 17 away from the central portion of the spring 19 a sufficient distance to snap the spring 19 rearwards across its dead center. After the spring crosses its dead center, it will press the member 17 into its open or tie-releasing position as shown in Fig. 1.

The operation is as follows:

When the holder is in its open position, the front and back members will be held spread apart by the bow-spring 19 as shown in Fig. 1. The spring will be rearwardly bowed by the hook ends 28 of the forwardly bowed front member 17 and will hold said member 17 spaced from the forwardly bowed front section 23 of the back mem-

ber 15. The outer end portions of the spring 19 and the section 23 will be outwardly divergent to facilitate placement of the inturned folds 14 on the wide end of the tie, between the spring 19 and the section 23. The front panel 10 of the shirt and the narrow end 12 of the tie will then be inserted between the sections 21 and 23 of the back member 15 and gripped thereby due to the resilient action of the bend 24. The front 13 of the wide end of the tie will then be placed around the front member 17 and its inturned folds 14 inserted between the end portions of the spring 19 and the front section 23 of the back member 15. When the tie and shirt are thus positioned in the holder, the user will exert sufficient backward pressure against the front 13 of the tie and the member 17 to snap bow-spring 19 forwardly across its dead center. When the spring becomes reversely bowed it exerts backward pressure on the front member 17 as shown in Fig. 2. The front 13 of the wide end of the tie will then be held in place by the rearwardly bowed front member 17, and the folds 14 of the tie will be tightly gripped between the hooks 28 of front member 17 and the end portions of the front face of the front section 23 of the back member 15. When the front member 17 moves backwardly, the pins 40 and 41 pass through the holes 33 in the spring 19, the folds 14 of the tie, and the holes 34 in the section 23 of the back member 15. The pins 40 will also pass through the small tie end 12, the shirt panel 10 and the hole 45 in the back section 21 of the back member 15. The tie will then be firmly secured in its proper position on the shirt, both ends of the tie will be secured against relative displacement, and the front member 17 will be concealed by the front of the wide end of the tie. This closing of the holder completes the securing of the tie and shirt as desired and is completed when backward pressure is exerted against the front member 17 to reverse the action of the bow spring 19.

If desired, the pins 40 and 41 may be omitted. The front 13 and the folds 14 of the large tie end may be then placed in the position shown in Fig. 1 and the front member operated to close the holder and grip said portions of the tie, and the narrow portion 12 of the tie and the shirt panel 10 may then be inserted between the sections 21 and 23 of the back member 15 to complete the tie-securing operation.

When the holder is to be opened for the release of the tie, the user will exert backward pressure against the free ends of one or both of the fingers 36, so they will fulcrum on the ends of the clip 32 and pry apart the central portions of the spring 19 and the front member 17 sufficiently to snap the spring across its dead center and cause it to be flexed into its reversely bowed position. The spring 19 will then hold the member 17 in its open or tie-releasing position. The front member 17 is bowed so it can straighten to permit its hooks 28 to expand so that the spring can be operated across its dead center.

If desired, the holder may also be opened by the user's fingers by prying the ends of the member 15 away from the ends of the front member 17 in order to snap the spring 19 rearwards across its dead center.

The invention exemplifies a neck-tie holder which is completely concealed by the tie; firmly secures both ends of the tie and a panel of the shirt together; holds the front of the tie in shape; can be easily manipulated into its open or closed positions; can be made, mainly, from

strip metal; includes a two-way action bow-spring for holding the members in open and closed positions; and can be fabricated at a low cost.

The invention is not to be understood as restricted to the details set forth since these may be modified within the scope of the appended claims without departing from the spirit and scope of the invention.

Having thus described the invention, what I claim as new and desire to secure by Letters Patent is:

1. As a new article of manufacture, a holder adapted to retain the wide and narrow ends of a tied conventional four-in-hand tie in place with respect to a front portion of the user's shirt and comprising a horizontally elongated front member adapted to fit behind the wide end of the tie and have the usual infolds of the wide tie end lapped around its ends, a horizontally elongated back member positioned behind the front member and adapted to grip the narrow end of the tie and the shirt front portion, and a spring disposed between, and extending lengthwise of, the front and back members, having its central portion supported by the center portion of said back member and positioned with respect to the front and back members so that it is capable of flexing forwardly and rearwardly, securing means supported by said front member for retaining said spring in either one of said flexed positions whereby when it is flexed rearwards with respect to the front member and past its dead center it holds the front member in an open position wherein its ends are spaced forwards from the ends of the back member and permit the infolds of the wide tie end to be lapped around them or removed therefrom and when flexed forwards with respect to the front member and past its dead center it yieldingly holds the front member in a closed position wherein its ends clamp the infolds of the wide end of the tie against the ends of said back member.

2. As a new article of manufacture a holder adapted to retain the wide and narrow ends of a tied conventional four-in-hand tie in place with respect to a front portion of the user's shirt and comprising a horizontally elongated front member adapted to fit behind the wide end of the tie and have the usual infolds of the wide tie end lapped around its ends, a horizontally elongated U-shaped back member formed of spring material, positioned behind the front member, embodying front and back sections, and adapted yieldingly to grip between its front and back sections the narrow end of the tie and the shirt front portion, and a spring disposed between, and extending lengthwise of, the front and back members, having its central portion supported by the center portion of said back member and positioned with respect to the front and back members so that it is capable of flexing forwardly and backwardly, securing means supported by said front member for retaining said spring in either one of said flexed positions whereby when it is flexed rearwards with respect to the front member and past its dead center it holds the front member in an open position wherein its ends are spaced forwards from the ends of the front section and permit the infolds of the wide tie end to be lapped around them or removed therefrom and when flexed forwards with respect to the front member and past its dead center it yieldingly holds

the front member in a closed position wherein its ends clamp the infolds of the wide end of the tie against the ends of said front section.

3. As a new article of manufacture, a holder adapted to retain the wide and narrow ends of a tied conventional four-in-hand tie in place with respect to a front portion of the user's shirt and comprising a horizontally elongated forwardly bowed front member adapted to fit behind the wide end of the tie and provided at the ends thereof with rearwardly and inwardly extending hooks adapted to have the usual infolds of the wide tie end lapped around them, a horizontally elongated back member positioned behind, and in substantially parallel relation with, the front member and adapted to grip the narrow end of the tie and the shirt front portion, and a two-position bow-spring disposed between, and extending lengthwise of, the front member and the back member, having its central portion connected to the central portion of said back member, and having its ends fitting within the hooks and so operatively connected thereto that when it is flexed rearwards with respect to the front member and past its dead center it holds the front member in an open position wherein the hooks are spaced forwards from the ends of the back member and permit the infolds of the wide tie end to be lapped around them or removed therefrom and when flexed forwards with respect to the front member and past its dead center it yieldingly holds the front member in a closed position wherein the hooks clamp the infolds of the wide end of the tie against the ends of said back member.

4. As a new article of manufacture, a holder adapted to retain the wide and narrow ends of a tied conventional four-in-hand tie in place with respect to a front portion of the user's shirt and comprising a horizontally elongated forwardly bowed front member adapted to fit behind the wide end of the tie and provided at the ends thereof with rearwardly and inwardly extending hooks adapted to have the usual infolds of the wide tie end lapped around them, a horizontally elongated U-shaped back member formed of spring material, positioned behind, and in substantially parallel relation with, the front member, embodying front and back sections, and adapted yieldingly to grip between its front and back sections the narrow end of the tie and the shirt front portion, and a two-position bow-spring disposed between, and extending lengthwise of, the front member and the front section of the back member, having its central portion connected to the central portion of said front section, and having its ends fitting within the hooks and so operatively connected thereto that when it is flexed rearwards with respect to the front member and past its dead center it holds the front member in an open position wherein the hooks are spaced forwards from the ends of the front section and permit the infolds of the wide tie end to be lapped around them or removed therefrom and when flexed forwards with respect to the front member and past its dead center it holds the front member in a closed position wherein the hooks clamp the infolds of the wide end of the tie against the ends of the front section.

5. As a new article of manufacture, a holder adapted to retain the wide and narrow ends of a tied conventional four-in-hand tie in place with respect to a front portion of the user's shirt and comprising a horizontally elongated, forwardly

bowed front member adapted to fit behind the wide end of the tie and have the usual infolds of the wide tie end lapped around its ends, a horizontally elongated back member formed of thin strip material, positioned behind, and in substantially parallel relation with, the front member, provided at its central portion with a forwardly extending offset, and adapted to grip the narrow end of the tie and the front shirt portion, and a two-way bow-spring disposed between, and extending lengthwise of, the front member and the back member, having its central portion connected to the aforesaid offset by a C-shaped clip, and having its ends so operatively connected to the front member that when it is flexed rearwards with respect to the front member and past its dead center it holds the front member in an open position wherein its ends are spaced forwards from the ends of the back member and permit the infolds of the wide tie end to be lapped around them or removed therefrom and when flexed forwards with respect to the front member and past its dead center it yieldingly holds the front member in a closed position wherein its ends clamp the infolds of the wide end of the tie against the ends of said back member.

6. As a new article of manufacture, a holder adapted to retain the wide and narrow ends of a tied conventional four-in-hand tie in place with respect to the front portion of the user's shirt and comprising a horizontally elongated front member adapted to fit behind the wide end of the tie and have the usual infolds of the wide tie end lapped around its ends, a horizontally elongated U-shaped back member formed of spring material, positioned behind the front member, embodying front and back sections, adapted yieldingly to grip between its front and back sections the narrow end of the tie and the shirt front portion, and provided with a transverse hole inwards of one end of its front section, a spring disposed between, and extending lengthwise of, the front and back members, having its central portion supported by the center portion of said back member, positioned with respect to the front and back members so that it is capable of flexing forwardly and rearwardly, and embodying inwards of one end thereof a transverse hole in alignment with the hole in said front section, securing means supported by said front member for retaining said spring in either one of said flexed positions whereby when it is flexed rearwards with respect to the front member and past its dead center it holds the front member in an open position wherein its ends are spaced forwards from the ends of the front section and permit the infolds of the wide tie end to be lapped around them or removed therefrom and when flexed forwards with respect to the front member and past its dead center it yieldingly holds the front member in a closed position wherein its ends clamp the infolds of the wide end of the tie against the ends of said front section, and a pin connected to, and projecting rearwards from, the front member, aligned with the two aforementioned holes, and adapted when the front member is manipulated into its closed position to pass through the hole in the bow-spring, the adjacent infold of the front end of the tie, the hole in the front section of the back member and the narrow end of the tie.

7. As a new article of manufacture, a holder adapted to retain the wide and narrow ends of a tied conventional four-in-hand tie in place with

respect to a front portion of the user's shirt and comprising a horizontally elongated, forwardly bulged front member adapted to fit behind the wide end of the tie and provided at the ends thereof with rearwardly and inwardly extending hooks adapted to have the usual infolds of the wide tie end lapped around them, a horizontally elongated U-shaped back member formed of spring material, positioned behind, and in substantially parallel relation with the front member, embodying front and back sections, adapted yieldingly to grip between its front and back sections the narrow end of the tie and the shirt front portion, and provided with transverse holes inwards of the ends of its front section, a two-position bow-spring disposed between, and extending lengthwise of, the front member and the front section of the back member, having its central portion connected to the central portion of said front section, embodying inwards of its ends transverse holes in alignment with the holes in said front section, and having its ends fitting within the hooks and so operatively connected thereto that when it is flexed rearwards with respect to the front member and past its dead center it holds the front member in an open position wherein the hooks are spaced forwards from the ends of the front section and permit the infolds of the wide tie end to be lapped around them or removed therefrom and when flexed forwards with respect to the front member and past its dead center it holds the front member in a closed position wherein the hooks clamp the infolds of the wide end of the tie against the ends of the front section, and a pair of laterally spaced pins connected to, and projecting rearwards from, the end portions of the front member, aligned with the aforesaid holes and adapted when the front member is manipulated into its closed position to pass through the holes in the bow-spring, the infolds of the wide tie end, the holes in the front section of the back member, and the narrow end of the tie.

8. As a new article of manufacture, a holder adapted to retain the wide and narrow ends of a tied conventional four-in-hand tie in place with respect to a front portion of the user's shirt and comprising a horizontally elongated front member adapted to fit behind the wide end of the tie and have the usual infolds of the wide tie end lapped around its ends, a horizontally elongated back member positioned behind the front member and adapted to grip the narrow end of the tie and the shirt front portion, and a spring disposed between, and extending lengthwise of, the front and back members, having its central portion supported by the center portion of said back member and positioned with respect to the front and back members so that it is capable of flexing forwardly and rearwardly, securing means supported by said front member for retaining said spring in either one of said flexed positions whereby when it is flexed rearwards with respect to the front member and past its dead center it holds the front member in an open position wherein its ends are spaced forwards from the ends of the back member and permit the infolds of the wide tie end to be lapped around them or removed therefrom and when flexed forwards with respect to the front member and past its dead center it yieldingly holds the front member in a closed position wherein its ends clamp the infolds of the wide end of the tie against the ends of said back member, and movable means whereby after the front

member is in its closed position the front and back members may be pried apart in order to effect such flexing of the bow-spring as to cause the front member to move into its open position.

9. As a new article of manufacture, a holder adapted to retain the wide and narrow ends of a tied conventional four-in-hand tie in place with respect to a front portion of the user's shirt and comprising a horizontally elongated front member adapted to fit behind the wide end of the tie and have the usual infolds of the wide tie end lapped around its ends, a horizontally elongated U-shaped back member formed of spring material, positioned behind the front member, embodying front and back sections, and adapted yieldingly to grip between its front and back sections the narrow end of the tie and the shirt front portion, a spring disposed between, and extending lengthwise of, the front and back members, having its central portion supported by the center portion of said back member and positioned with respect to the front and back members so that it is capable of flexing forwardly and rearwardly, securing means supported by said front member for retaining said spring in either one of said flexed positions whereby when it is flexed rearwards with respect to the front member and past its dead center it holds the front member in an open position wherein its ends are spaced forwards from the ends of the front section and permit the infolds of the wide tie end to be lapped around them or removed therefrom and when flexed forwards

with respect to the front member and past its dead center it yieldingly holds the front member in a closed position wherein its ends clamp the infolds of the wide end of the tie against the ends of said front section, and means whereby after the front member is in its closed position the front and back members may be pried apart in order to effect such flexing of the bow-spring as to cause the front member to move into its open position, said means comprising a pair of complementary oppositely disposed transversely movable finger-like elements positioned adjacent the central portion of the spring.
